UNITED STATES PATENT OFFICE.

ROY N. CUNNINGHAM AND JOHN W. McPHERSON, OF COLUMBUS, OHIO.

NON-REFILLABLE RECEPTACLE.

No. 874,739.

Specification of Letters Patent.

Patented Dec. 24, 1907.

Application filed April 1, 1907. Serial No. 365,695.

To all whom it may concern:

Be it known that we, ROY N. CUNNINGHAM and JOHN W. McPHERSON, citizens of the United States, residing at Columbus, in the county of Franklin and State of Ohio, have invented certain new and useful Improvements in Non-Refillable Receptacles, of which the following is a specification.

Our invention relates to non-refillable liquor receiving receptacles and has for its object the provision of a device of this character which may be very cheaply made and which after being once emptied, cannot be refilled.

Further objects and advantages of the invention will be set forth in the detailed description which now follows:

In the accompanying drawing: Figure 1 is a vertical section of a non-refillable receptacle, constructed in accordance with the invention, and, Fig. 2 is a plan view of said receptacle.

Like numerals designate corresponding parts in both of the figures of the drawing.

Referring to the drawing, the numeral 5 designates a glass body portion which is provided with a closed concaved top 6. An annular groove 7 is formed in the wall of this receptacle, of such configuration as to produce the sharp shoulder 8 (see Fig. 1). The body 5 is open at the bottom.

A piston-like bottom 9 also of glass, is annularly grooved as at 10 for the reception of a preferably cork packing ring 11. The upper face 12 of the bottom 9 is concaved and conforms to the curvature of the lower side of the top 6. An outlet tube 13 is in communication with the interior of the body portion 5 as at 14. This tube has a downwardly extending portion 15 at one side of the receptacle and an upwardly extending portion 16 at the opposite side of the receptacle, these two portions being connected by a horizontally disposed tube 17 and the portion 16 terminating in a spout 18.

The operation of the device is as follows: Before the bottom 9 is placed in position, the receptacle is held in an inverted position and filled with any desired liquid. Since the portion 17 of the outlet tube, lies below the top of the bottom 9, none of the liquid can pass through the tube during this filling operation. After the desired quantity of liquid has been placed in the receptacle, the bottom 9 is forced into position, the cork pack-

ing ring 11 being tightly compressed in its groove 10 when this is done. It is impossible after this point has been reached to remove the liquid from the bottle except by forcing the bottom 9 bodily into the receptacle 5, this bottom then acting much after the manner of a piston to force the liquid through the outlet tube 13 and from the spout 18. The convex lower face of the top 6 enters the concaved top 12 of the bottom 9, said concaved top of the bottom collecting the last few drops of liquor at a central point, from whence it may readily be forced through the tube 13 as the bottom 9 is forced into contact with the lower face of the top 6. When the bottom 9 reaches its upward limit of movement, the packing ring 11 expands into the groove 7 and is engaged by the sharp shoulder 8 to prevent retrograde movement of the bottom. The body portion 5 is now practically a bottomless receptacle and is not adapted to again serve the purposes set forth, for the bottom 9 closes the mouth of the outlet tube 13. It is impossible to remove this bottom 9 without breaking the receptacle 5, for this bottom will be made of heavier glass than the receptacle 5 and any attempt to break the bottom 9 to remove it, will result in breaking the main receptacle.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

What we claim, is:

1. In a device of the character described, the combination with a body portion closed at the top and open at the bottom, of an outlet tube leading from the upper portion of said receptacle to a point adjacent the lower end of the receptacle, said tube then being returned to a point adjacent the upper end of the receptacle, and a piston-like bottom disposed within the receptacle.

2. In a device of the character described, the combination with a body portion closed at the top and open at the bottom, of an outlet tube leading from the upper portion of said receptacle to a point adjacent the lower end

of the receptacle, said tube then being returned to a point adjacent the upper end of the receptacle, a piston-like bottom disposed within the receptacle, and means for locking 5 said piston-like bottom against retrograde movement after it reaches its limit of movement toward the top of the receptacle.

3. A non-refillable receptacle, comprising a body portion open at the bottom and closed 10 at the top, an outlet tube leading from the upper portion of the receptacle, and a piston-like bottom for the receptacle which is slidably disposed within said receptacle, the lower face of the top being convex and the 15 upper face of the bottom being concaved.

4. A non-refillable receptacle, comprising a body portion open at the bottom and closed at the top, an outlet tube leading from the 20 upper portion of the receptacle, a piston-like bottom for the receptacle which is slidably disposed within said receptacle, and means for locking said piston-like bottom against retrograde movement after it reaches its limit of movement toward the top of the 25 receptacle, the lower face of the top being con-

vex and the upper face of the bottom being concave.

5. In a device of the character described, the combination with a body portion closed at the top and open at the bottom, of an outlet tube leading from the tube which extends down one side of the receptacle to a point adjacent the bottom thereof, then partially around said receptacle and then up to a point above the top of the receptacle, there being 30 an annular groove formed in the wall of the receptacle adjacent the top thereof, a piston-like bottom slidably disposed within the receptacle, and an annular packing ring carried by said bottom which is adapted to expand 35 into said annular groove when the bottom reaches its limit of movement toward the top.

In testimony whereof we affix our signatures in presence of two witnesses.

ROY N. CUNNINGHAM.
JOHN W. McPHERSON.
